UNITED STATES PATENT OFFICE.

STEFFEN A. BROWN AND EDGAR W. BROCKMEYER, OF DAYTON, OHIO.

ELECTRIC MOTOR.

Application filed October 17, 1925. Serial No. 62,946.

Our invention relates to electric motors and in particular to the mounting of the brushes thereof.

It is the object of our invention to provide a single, unitary structure adapted to support a plurality of brushes and to maintain said brushes in a position in engagement with the commutator so that the brushes will be uniformly pressed against the commutator and will wear uniformly.

It is a further object to provide the means of forcing the brushes into engagement with the commutator so that not only will the pressure be equalized but that the heat generated due to current carried by the brushes and the contact of the brushes with the commutator will not be communicated to the springs and destroy the temper of the springs.

It is a further object to provide means of easily locking the brushes in their retracted position; each brush being independently retracted and locked with respect to the other brushes.

It is a further object to so arrange the brushes that they may be permitted to wear down to the connection of the shunt wire to the brush so as to secure the maximum of wear out of the brush.

It is a further object to provide a construction in which a long brush may be utilized.

Referring to the drawings:

Fig. 1 is a plan view of the brush holder and brushes showing two of the brushes in a normal position of contact with the fragmentary portion of the commutator illustrated, a third brush fully extended showing the extent to which the brush may be forced inwardly and therefore used up, and showing the fourth brush in locked position with its housing in section;

Fig. 2 is a side elevation in section of the brush housing showing the method of supporting an individual brush in relation to the commutator;

Fig. 3 is an end elevation of one of the brushes showing the groove.

Referring to these drawings in detail, 1 is a supporting brush ring either made of a casting or of a stamping and of such material as may be desired. This ring carries a plurality of terminals such as 2 which carry the shunt wires 3, such wires having their free ends embedded in the inner end, as at 4, of the brush 5. The brush is provided at its

outer end with a transverse groove 6 in which rides the rounded head 7 of an impeller arm 8. This impeller arm is pivoted midway between adjacent brushes on the brush ring as at 9. Two of such arms are pivoted on a single pivot 9. Approximately one-third of the distance from the free ends of the arms on the inner sides thereof are eyes 10 to which are connected springs 11, there being a spring to each two arms, the spring connecting the arms tending to draw them together and thereby force the brushes against which the arms rest inwardly against the commutator. This arrangement equalizes the pressure on the brushes and enables the brushes to be moved the full depth inwardly to use up the entire brush without binding in the brush guide or holder 12. There is one brush guide or holder mounted on the inner periphery of the ring 1 for each brush. This brush holder has its near edge necessarily an appreciable distance from the commutator surface. The brush holder consists of a plate 13 and a U-shaped guide member 14 with slots 15 in its side walls and flaring flanges 16 used for attaching this U-shaped member by the bolts 17 or screws to the plate 13 and the supporting ring.

It will be observed that this arrangement of engaging the brushes with the arms permits the radiation of the heat and thereby prevents the drawing of the temper of the spring 11.

When it is desired to hold the brush out of operation the brush can be pulled outwardly either by grasping the brush or the shunt wire and pulling it into the position shown at the bottom of Figure 1, allowing the head 7 of the arm 8 to rest against the side preventing it from returning. The pressure of the spring 11 drawing the arm inwardly forces the brush against the side wall of the brush guide preventing its movement.

It is understood that we desire to comprehend within our invention such modifications as may be necessary to adapt the invention to varying conditions of use.

Having thus fully described our invention, what we claim as new and desire to secure by Letters Patent, is:

1. In a brush holder, a supporting means, brush guides mounted thereon, brushes therein, impeller arms pivoted on said supporting means having their free ends engaging with

the ends of the brushes, and a yielding means for drawing said impeller arms to one another and thereby forcing the brushes inwardly.

5. 2. In a brush holder, a supporting means, brush guides mounted thereon, brushes therein, impeller arms pivoted on said supporting means having their free ends engaging with the ends of the brushes, and a yielding means 10 for drawing said impeller arms to one another and thereby forcing the brushes inwardly, said impeller arms being pivoted on a common pivot.

3. In a brush holder, a supporting means, 15 brush guides mounted thereon, brushes therein, impeller arms pivoted on said supporting means having their free ends engaging with the ends of the brushes, and a yielding means for drawing said impeller arms to one another and thereby forcing the brushes inwardly, said impeller arms being pivoted on a common pivot, said brush guides having slots in their sides to accommodate the ends of the arms as they move inwardly.

25. 4. In a brush holder, a supporting means, brush guides mounted thereon, brushes therein, impeller arms pivoted on said supporting means having their free ends engaging with the ends of the brushes, and a yielding means 30 for drawing said impeller arms to one another and thereby forcing the brushes inwardly, said impeller arms being pivoted on a common pivot, said brushes having grooves in the ends thereof for accommodating the ends of the impeller arms.

5. In a brush holder, a supporting ring, a plurality of inwardly projecting brush holders, brushes therein adapted to reciprocate therein, said holders having means for 40 accommodating the ends of shunt wires and brush impellers, pairs of brush impellers located between pairs of brushes pivoted on said supporting means and yielding means connected inwardly between said impellers 45 to the impellers at points remote from their extreme ends, said extreme ends engaging with said brushes.

6. In a brush holder, a supporting ring, a plurality of inwardly projecting brush 50 holders, brushes therein adapted to reciprocate therein, said holders having means for accommodating the ends of shunt wires and brush impellers, pairs of brush impellers located between pairs of brushes pivoted on said supporting means, and yielding means 55 connected inwardly between said impellers to the impellers at points remote from their extreme ends, said extreme ends engaging with said brushes, said brushes having 60 grooves on the outer ends thereof for accommodating the ends of said impellers.

7. In a brush holder, a ring, a plurality

of spaced guides for brushes, brushes reciprocating therein, means of pivoting impeller arms located on said rings between 65 said guides, impeller arms pivoted thereon having their free ends engaging with said brushes, said guides being adapted to permit the ends of the arms to pass therethrough, and yielding means between said 70 arms to draw them together and to force the brushes inwardly, said arms being appropriately arranged at an angle of ninety degrees from one another, said angle decreasing as the brushes are worn. 75

8. In a brush holder, a supporting means, guide means for brushes, brushes reciprocating therein, impelling means, yielding means to actuate the impelling means, which impelling means engages with the brushes, said means being so arranged that when the brushes are retracted a predetermined distance the impelling means will engage with the sides of the brushes and so bind them in the guide of the brush that the brush will be held in a predetermined position out of engagement with its commutator. 80

9. In a brush holder, a supporting means, guide means for brushes, brushes reciprocating therein, impelling means, yielding means to actuate the impelling means, which impelling means engages with the brushes, said means being so arranged that when the brushes are retracted a predetermined distance the impelling means will engage with the sides of the brushes and so bind them in the guide of the brush that the brush will be held in a predetermined position out of engagement with its commutator. 90

95

10. In a brush support, a ring having spaced terminals for shunt wires and spaced supports for brush guides, brush guides, brushes therein adapted to reciprocate, grooves in the outer ends of said brushes, impeller arms pivoted on said ring between 100 said guides and a yielding means between said arms spaced from the free ends thereof, the free ends of the arms being adapted to ride in the grooved end of the brushes, said guides having slots on the sides thereof for accommodating the shunt wires and ends of the impeller arms. 105
